(57) **CLAIM**

The ornamental design for a scent warmer, as shown and described.

DESCRIPTION

FIG. 1 is a front elevation view of a scent warmer.

FIG. 2 is a front elevation view of the scent warmer of FIG. 1 including a screen design, according to an embodiment of the disclosure.

FIG. 3 is a rear elevation view of the scent warmer of either of FIGS. 1 and 2.

FIG. 4 is a left side elevation view of the scent warmer of any of FIGS. 1 through 3. FIG. 4 is also a right side elevation view of the scent warmer of any of FIGS. 1 through 3.

FIG. 5 is a partially exploded, front elevation view of the scent warmer of FIG. 1.

FIG. 6 is a partially exploded, rear elevation view of the scent warmer of any of FIGS. 1-5.

FIG. 7 is a partially exploded, left side elevation view of the scent warmer of any of FIGS. 1-6. FIG. 7 is also a partially exploded, right side elevation view of the scent warmer of any of FIGS. 1-6.

FIG. 8 is a top plan view of the scent warmer of any of FIGS. 1-7.

FIG. 9 is a bottom plan view of the scent warmer of any of FIGS. 1-8.

FIG. 10 is a front elevation view of another scent warmer.

FIG. 11 is a front elevation view of the scent warmer of FIG. 10 including the screen design according to an embodiment of the disclosure.

FIG. 12 is a rear elevation view of the scent warmer of either of FIGS. 10 and 11.

FIG. 13 is a left side elevation view of the scent warmer of any of FIGS. 10 through 12. FIG. 13 is also a right side elevation view of the scent warmer of any of FIGS. 10 through 12.

FIG. 14 is a partially exploded, front elevation view of the scent warmer of FIG. 10.

FIG. 15 is a partially exploded, rear elevation view of the scent warmer of any of FIGS. 10-14. FIG. 16 is a partially exploded, left side elevation view of the scent warmer of any of FIGS. 10-15. FIG. 16 is also a partially exploded, right side elevation view of the scent warmer of any of FIGS. 10-15.

FIG. 17 is a top plan view of the scent warmer of any of FIGS. 10-16.

FIG. 18 is a bottom plan view of the scent warmer of any of FIGS. 10-17; and,

FIG. 19 is a front elevation view of the screen design of FIGS. 2 and 11.

In the figures, the broken lines, showing an environment in which the design may be used, are for illustrated purposes only and form no part of the claimed design.
